US0D1065973S

(12) **United States Design Patent** (10) **Patent No.:** **US D1,065,973 S**
(45) **Date of Patent:** **** Mar. 11, 2025**

(54) **D-LOCK**

(71) Applicant: **Zeal Innovation Ltd.**, Swansea (GB)

(72) Inventor: **Neil Anthony Barron**, Swansea (GB)

(73) Assignee: **Zeal Innovation Ltd.**, Swansea (GB)

(**) Term: **15 Years**

(21) Appl. No.: **29/793,533**

(22) Filed: **Mar. 29, 2023**

(51) **LOC (15) Cl.** **08-07**

(52) **U.S. Cl.**

USPC **D8/333**

(58) **Field of Classification Search**

USPC D8/330-334, 336, 339, 341, 356, 383

CPC E05B 67/003; E05B 73/0005; E05B 71/00

See application file for complete search history.

(57) **CLAIM**

The ornamental design for a D-lock as shown and described.

DESCRIPTION

FIG. 1 is a front elevation view of the D-lock;

FIG. 2 is a right side elevation view of the D-lock;

FIG. 3 is a front and right side perspective side view of the D-lock; and,

FIG. 4 is a bottom view of the D-lock.

The broken lines shown in the figures depict portions of the D-lock that form no part of the claimed design.

1 Claim, 4 Drawing Sheets
